WORK TABLE WITH SINE BAR
ADJUSTMENTLouis Edwin Sealey, Carsham, England, assignor
to Papworth Limited, Bristol, England, a
British companyApplication February 4, 1944, Serial No. 521,157
In Great Britain November 10, 1941

4 Claims. (Cl. 90—58)

1

The subject of this invention is a work table for precision work, which can be set firmly and accurately to any simple or compound angle, its chief object being to provide a wider range of operation and a greater degree of accuracy than can be obtained by other devices used for similar purposes. For these purposes I utilize a known arrangement, of the kind in which a circular work table rotatable about its own centre is also mounted to swing in a vertical plane, that is, its axis of rotation can be tilted about a shaft or bearing member in a pillar on the base of the device.

According to the present invention, the shaft itself is pivotally connected with the pillar, enabling a third adjustment to be effected to produce a compound angle of tilting of the table. The extent of adjustment in any plane is regulated by a sine bar, and locking means are provided to secure the table firmly in the positions to which it has thus been adjusted.

In order that the said invention may be clearly understood and readily carried into effect, the same will now be described more fully with reference to the drawings accompanying which illustrate an exemplification of the invention.

Figure 1 represents the apparatus in side elevation, with the work table in zero or horizontal position.

Figure 2 is a view corresponding with that in Figure 1, but with the table swung through an angle of 90 degrees into a vertical position.

Figure 3 is a plan of the table, partly broken away to enable the locking mechanism of the table to be seen.

Figure 4 is an elevation viewed at right angles to that in Figure 1.

Figure 5 is an elevation corresponding with that in Figure 4, with the table swung to the left 90 degrees into a vertical position.

Figure 6 is a view similar to that in Figure 5, but with the table swung to the right through 45 degrees.

Figure 7 is a view similar to Figure 1, with some parts omitted, to show the sine bar in one of its zero positions.

Figure 8 is a view similar to Figure 2 showing the sine bar with slip gauges between its disc d^1 and the setting pad h^1 .

Figure 9 is a plan; and Figures 10, 11, and 12, elevations similar to Figures 4, 5, and 6 respectively, showing the sine bar in position in each case.

In the drawings e indicates a bed or base plate, on which is a pillar 51 to which a shaft c is

5 hinged by a pin d . A bearing a carrying the work table b and comprising hangers $52, 53$ embracing the shaft is capable of a movement of rotation about the said shaft c . The end of the shaft remote from its pivot pin d is supported by a bearing head g , and the head g is in turn supported by two pairs of links u and v , the links u being pivotally connected at x with the base e , and the links v pivotally connected with the head g at w . An arm a^1 pivoted at b^1 to the base e passes through a block y at which the links u and v meet, and as the lower half of this block is split, and a pin z connecting the two pairs of links passes through the said lower half, when the pin z is tightened the block and links are thereby secured in adjusted position, as seen clearly in Figure 2.

10 On the base e are stops or abutments f, i, l, n , and o and stops j, j^1 , and k depend from the bearing a . A sine bar f^1 having at one end a disc d^1 can be attached at either side of pin d , at x^1 or y^1 (Figure 9) and at the end of the extension shaft c^2 at z^1 which shaft is concentric with shaft c , but is fixed to and moves with, 15 table support a . As seen in Figure 4, a slip h can be inserted between the stops i and j to support the table in a position parallel with the base, although the table is free to swivel about the shaft c . The periphery of the table b is graduated as seen in Figure 1, and in the table top are four T slots 54 (see Figure 3) in square formation, for the attachment of the work-piece to the table. In the zero position, that is with "0" on the table graduations opposite "0" on a 20 graduated plate s on the bearing a , two of these slots are exactly parallel with the centre line of the hinged shaft c , and the other two slots exactly at right angles thereto. A tapered spigot r is permanently secured to the table b , and 25 can be gripped by a taper bored band q controlled by a screw p . By turning the screw p in an anti-clockwise direction the band q is allowed to release its hold on the spigot r , when the table can be rotated about its centre until the angle required can be read from the graduations 30 marked on the periphery of the table and those on the graduated plate s . The screw is then tightened to lock the table in the position required.

35 In the position shown in Figure 2, the table b and shaft c are swung about the hinge d of the latter until the stop j^1 on the hinge pin meets the stop o on the base e .

To move the table into the position shown in Figure 5, the slip h is removed and the table on

its bearing *a* swung around the shaft *c* until the stop *k* on the bearing rests on the stop *l* on the base. When the table is swung over to the other side through an angle of 45 degrees, as seen in Figure 6, the stop *j* on the bearing *a* meets the stop *n* on the base *e*.

In order that the table may be locked in any position to which it has been swung around the shaft *c*, the bearing support *a* is split, and two screws *t* passed through the bifurcated lower portion thereof, each of the said screws having square portions at each end, so that the screws can be tightened or slackened from either side which may be easily accessible when the table has been tilted about the shaft *c*, for instance as in Figure 5 or Figure 6.

Assuming for example that a tilting angle of 10 degrees is required in the plane of swinging about the hinge pin *d*, and an angle of 22 degrees in the plane of swinging about the axis of the shaft *c*, it is necessary in the first place to ascertain that the stops *g* and *f* meet (see Figure 1) then a slip *h* 2.25 inches long is inserted between the stops *i* and *j* (Figure 4) thus bringing the table into a true horizontal plane with the base *e*; the table is pushed firmly toward the base and locked relatively to the shaft *c* by means of the two screws *t* and the screw *z* passing through the clamping block *y*, the sine bar *f*¹ fixed on the end of the shaft *c*² (Figure 9) and a 1 inch slip *g*¹ placed between the abutment *c*¹ on the base and the disc *d*¹ on the sine bar (Figure 10), the nut *e*¹ tightened on the extension of shaft *c*² concentric with shaft *c* so as to clamp the sine bar *f*¹, at the same time applying a light pressure on the disc *d*¹ to make contact with the slip *g*¹. The constant for 22 degrees is then selected from the sine bar table (5'') which is 1.873, and a combination of slips to make up this figure is then required. The two screws *t* (Figure 2) are then slackened and the table tilted, bringing the sine bar *f*¹ away from the 1' slip gauge *g*¹ until the stops *k* and *l* meet. The slips making up the combination are now placed on top of the 1 inch slip *g*¹, or alternatively the 1 inch slip can be removed and 1 inch added to make the combination 2.873. The table is then swung lightly back until the disc *d*¹ of the sine bar makes contact with the top of the slips, the two screws *t* locked, and the nut *e*¹, sine bar and slips removed. Next, to obtain the angle of 10 degrees in the plane swivelling about the pin *d*, the sine bar is attached to the pin *d* in the position marked *y*¹ in Figure 9, again placing a 1 inch slip between the disc *d*¹ of the sine bar and the abutment *h*¹ on the base *e* and the locking operation is repeated. The sine bar is then in a true parallel plane with the base *e*. The constant for 10 degrees is given as .8682, so that if the screw *z* is slackened and the table pushed back until the hinge pin projection *j*¹ meets the stop pin *o* (Figure 2) slips can be placed on top of the 1 inch slip to give 1.8682, then the table brought down until the disc *d*¹ touches the top of the slips, the screw *z* is locked, and the sine bar, nut *e*¹ and slips removed. The table is now ready for use with a compound angle the components

of which are 10 degrees and 22 degrees respectively.

What I claim as my invention and desire to secure by Letters Patent of the United States is:

1. In a work table, a base, a pillar rising from said base, a shaft pivotally mounted on said pillar to swing in a vertical plane, a bearing to carry a work table, said bearing comprising dependent members rockable on said shaft in a vertical plane at right angles with the aforesaid vertical plane, said work table being rotatable on said bearing to obtain a compound adjustment of said work table, an arm pivoted on said base carrying a bifurcated block, said block being movable longitudinally of said arm, links pivoted to said base and to said bearing respectively and having their joint meeting at said block, a pin connecting said links and passing through the split part of said block to tighten the latter to maintain the said links and bearing in the position to which they have been adjusted.

2. In a work table, a base, a pillar rising from said base, a shaft pivotally mounted on said pillar to swing in a vertical plane, a bearing mounted on said shaft to swing in a plane at right angles with said vertical plane, a table carried on and rockable integrally with said bearing in a vertical plane and rotatable thereon to obtain a compound adjustment of said work table, locking means provided to maintain said adjustment, and stops arranged to permit location of the work table positively in horizontal and vertical positions.

3. In a work table, a base, a pillar rising from said base, a shaft pivotally mounted on said pillar to swing in a vertical plane, a bearing mounted on said shaft to swing in a plane at right angles with said vertical plane, a table carried on and rockable integrally with said bearing in a vertical plane and rotatable thereon to obtain a compound adjustment of said work table, locking means provided to maintain said adjustment, stops arranged to permit location of the work table positively in horizontal and vertical positions, and further stops permitting location of the work table in a plane inclined at 45° to the horizontal in a movement of adjustment about said shaft.

4. In a work table, a base, a pillar rising from said base, a pivot pin carried in the pillar, a shaft upon the pivot pin and disposed perpendicularly thereto for swinging in a vertical plane, a bearing to carry a work table, said bearing comprising dependent members rockable on said shaft in a vertical plane at right angles with the aforesaid vertical plane, said work table being rotatable on said bearing to obtain a compound adjustment of said work table, a sine bar, means upon the pivot pin of said shaft and the shaft itself for removable attachment of said sine bar to permit the latter to co-operate with interchangeable slip pieces and thus to regulate the adjustment of the pivot pin and shaft relatively to the base, and locking means to maintain the said adjustment.

LOUIS EDWIN SEALEY.
